UNITED STATES PATENT OFFICE.

HARRY E. SWARTZ, OF READING, PENNSYLVANIA.

DESIGN FOR A SCREW-DRIVER.

SPECIFICATION forming part of Design No. 28,691, dated May 24, 1898.

Application filed March 31, 1898. Serial No. 675,998. Term of patent 7 years.

To all whom it may concern:

Be it known that I, HARRY E. SWARTZ, a citizen of the United States, residing at Reading, in the county of Berks and State of Pennsylvania, have invented and produced a new and original Design for Screw-Drivers, of which the following is a specification, reference being had to the accompanying drawings, forming part thereof.

10 Figure 1 is a plan view of a screw-driver, showing my new design. Fig. 2 is a sectional view.

15 As shown in the drawings, the leading or material feature of my design consists of a handle A in the shape of an oval ring, being filled in with a flat sheet B, and a lateral arm

C, projecting from the point of the oval, tapering in width toward its outer end, which is beveled on top and bottom, the lateral arm forming the blade and tapering at its junction with the handle in curved lines, as at D, to the edges of the handle.

Having fully described my invention, what I claim as new, and desire to secure by Letters Patent, is—

25 The design for a screw-driver herein shown and described.

HARRY E. SWARTZ.
